UNITED STATES PATENT OFFICE

FRANK HOWARD POCHIN, OF LEICESTER, ENGLAND

HEEL-ATTACHING MACHINE

Application filed October 15, 1927. Serial No. 226,478.

This invention has reference to improvements in heel attaching machines and its object is the provision of a simple, inexpensive, manually operable machine that is particularly suitable for use by shoe repairers and makers in a small way of business.

My invention is illustrated in the accompanying drawings, in which Fig. 1 is a side elevation thereof; Fig. 2 is a sectional view 10 of the shoe supporting and nail driving means; Fig. 3 is a sectional view of means for engaging the rear of a heel; and Fig. 4 is a detail to be referred to.

In said drawings, the numeral 4 indicates 15 a suitably shaped frame which is provided in its base with a vertical bearing to receive slidably therein a sleeve 5 that carries the shoe supporting and nail driving means.

Said sleeve is provided with an extension 20 6, having a rack 7. In gear with said rack is a pinion 8 mounted on a spindle which is adapted to be rotated in either direction (thereby raising or lowering the sleeve 5) by a hand lever 10.

25 The sleeve 5 is provided with a recess or socket into which the lower end 45 of a rod 12 is placed. Said rod has an annular shoulder 13 on which a spring 14 is supported. A shoe support 16 is provided that has a depending tubular extension 11 in which the rod 12 and spring 14 are slidably received. Said tubular extension is counterbored to provide an annular shoulder 17 against which the upper end of the spring engages.

30 The upper end 37 of the rod 12 is reduced, thereby forming an annular shoulder 41. The upper half of the reduced portion is provided with a screw thread, whilst the lower half thereof is left plain. A presser plate 23 rests on the shoulder 41 and nail drivers 18 are clamped thereon by a plate 21.

40 The drivers 18, plates 21 and 23, and the upper end of the rod 12, are all contained or received, and adapted for sliding movement, in a recess 9 provided in the upper part of the support 16.

45 When fitting the above described parts together, the drivers 18 (having enlarged lower ends) are inserted in apertures in the plate 21 and their upper ends are entered into aper-

tures 15 in the support 16. The drivers and plate 21 are then raised to permit insertion of the presser plate 23 into the recess 9 with one edge (which is preferably straight) against the vertical wall 39 of said recess. 55 The part 37 of the rod 12 is then passed through a central aperture in the plate 23, and screwed into a threaded aperture in the plate 21 by rotating said rod by a tommy placed in a hole 44 in the lower end of said 60 rod.

The drivers are thus neatly contained in the recess 9 and securely clamped to the rod 12 and are adapted for vertical movement relative to the support 16. Such movement 65 is limited by the contacting of the upper surface of the plate 21 with the upper wall 20 of the recess 9.

The dimensions of the various parts may be such as to permit the drivers to move until 70 their upper ends project one-sixteenth of an inch (more or less) above the surface of the support 16, so that the nails will be driven one-sixteenth of an inch below the surface of the insole inside the shoe. 75

It is sometimes desirable, however, to drive the nails flush with the surface of the insole, and in order to provide for a simple and speedy adjustment whereby this result may be attained, we provide a grub screw 26. By 80 screwing this down until it projects one-sixteenth of an inch into the recess 9, the movement of the drivers 18 will be further limited for the purpose stated.

If desired, the grub screw 26 may be 85 screwed down to project more than one-sixteenth of an inch into the recess, so that the nails will be left standing up a little above the surface of the insole.

Rotation of the shoe supporting and nail driving means is prevented by a screw 24 that engages in a guideway or slot 25 in the tubular extension 11 of the support 16. 90

The heel holding or clamping means comprise two members, one to engage the tread surface, and the other to engage the rear, of the heel. 95

The tread surface engaging member or anvil consists of a plate 30, pivotally supported on a block 31 which is carried on a 100

sort of collar 32. A stop screw 33 is provided in said collar against which the plate 30 is held by a spring 35. A very simple and quick adjustment of the angle of the plate with respect to the horizontal may be effected by adjusting the stop screw 33. This adjustment is necessary to ensure that the plate 30 will correctly engage the tread surfaces of heels differing in "pitch", i. e., heels the planes of the tread surfaces of which are at different angles with respect to the horizontal when placed on the support 16.

The collar 32 is clamped on the lower end of a spindle 36 the upper end of which is reduced at 34 and provided at that part with a left-hand screw thread which is screwed into an internal left-handed thread in a sleeve 38. The sleeve 38 is also provided with an external right-handed thread whereby it is screwed into the machine frame 4, and with a hand wheel 40. Rotation of the spindle 36 is prevented by a screw 42 that engages in a vertical slot or guideway 43 in said spindle.

The means above described are simple in construction and provide for a very rapid adjustment of the vertical position of the plate 30, for, on rotating the sleeve 38 by means of the hand wheel 40, the spindle 36 will move a distance equal to the sum of the pitches of the right-hand and left-hand threads respectively for each complete rotation of said sleeve. Further, by reason of the multiplied movement of the spindle 36 as above described, threads may be used having a sufficiently small pitch to prevent accidental displacement of the parts by pressure of the heel against the plate 30. A rapid adjustment is attainable by means of a single thread of large pitch, but means to prevent its accidental rotation must then be provided, with consequential complication of parts, increased cost, and loss of time in setting said means.

In order to prevent the heel from slipping backwards off the shoe, I provide a member to engage the rear face of the heel. Said member consists of a spindle 50 which may be provided with a pad 51 on its lower, heel-engaging, end. If desired, the lower end of said spindle may be flat (see Fig. 4) and a piece of rubber 58 placed thereon and held in position by a strip of leather 51.

Said spindle is carried and adjusted by means similar in construction to those described with reference to the spindle 36. That is to say, the spindle 50 is provided with a slot or guideway 56 engaged by a screw 55 whereby it is prevented from rotating and is reduced at 52 and provided at that part with a left handed thread whereby it is screwed into a hollow sleeve 53. Said sleeve is provided with an external right-handed thread whereby it is screwed into a screw-threaded part of the machine frame, and it is also provided with a hand wheel 54. By

these means, as already stated, a very rapid adjustment of the pad 51 may be effected without fear of its slipping back when the heel presses firmly against the pad due to the upward movement of the heel when the handle 10 is pulled forward.

When a heel is to be attached to a shoe, the operator places nails in the apertures 15. He then places the shoe upside down over the support 16, and the heel in position thereon. The plate 30 is adjusted according to the height and pitch of heel and the spindle 50 also will be adjusted to suit the heel. The support 16 may, if desired, be raised slowly until the heel contacts with the plate 30 and pad 51 in order to ascertain if the adjustments have been made correctly.

If a batch of shoes having heels of the same shape, height, and pitch, are to be operated on, the adjustments made for the first shoe will of course be suitable for all the shoes in the batch.

Having positioned the shoe and heel and made the adjustments referred to, the operator grasps the hand lever 10, and moves this smartly towards him, thereby raising the sleeve 5, through pinion 8, and consequently also the shoe support and nail driving means carried thereby. When the tread surface of the heel contacts with the plate 30, the heel, shoe, and support 16, will be arrested whilst the rod 12 and drivers 18 continue to move thereby driving the nails. The extent to which the rod and drivers move will, as already stated be determined by the upper surface of the plate 21 contacting with either the surface 20 or the screw 26.

Since the rod 12 was moved upwards relatively to the support 16, the spring 14 is compressed and therefore will tend in the early stage of the backward movement of the hand lever 10 to rotate the pinion 8 and thereby serve to or assist in returning the said lever and the parts controlled by it to their normal positions. This tendency will be augmented by the gravity of the shoe support and nail driving means. When, therefore, the operator has finished nailing a heel to a shoe, a very slight push sends the lever 10 backwards and returns all the parts to their normal lowermost positions so that the shoe can immediately be removed and another placed on the support.

It will be observed that the rod 12 (and parts carried thereby) can be lifted bodily out of the recess or socket in the sleeve 5. By this means provision is made for rapid adaptation of a single apparatus for securing heels to ladies' and men's shoes which of course vary considerably in dimensions; for if two rods 12 are provided—one carrying shoe supporting and nailing means for men's shoes, and the other carrying similar parts for operation on ladies' shoes—these may be rapidly interchanged according to the work

in hand. If desired, however, the rod 12 may be retained for heels of all shapes and sizes and only the parts 16, 18, and 21, interchanged.

5 What I claim is:—

An apparatus for attaching heels to boots and shoes, comprising a frame, a shoe-supporting member adapted for vertical movement therein and formed with a recess, the portion of said member above the recess having nail-receiving apertures, an actuating rod slidable vertically in said member, a driver plate carried by said rod and operating in said recess, nail drivers having heads at their lower ends resting against said driver plate, a clamping plate screw-threaded to the actuating rod and clamping the drivers to said driver plate, said drivers being of such a length that when the driver plate is at the lower limit of its movement the upper ends of the drivers are received in said apertures, and a grub screw in the apertured portion of said member which by its adjustment operates to limit the driving movement of the nail driver.
